UNITED STATES PATENT OFFICE.

GEORGE E. NEWELL AND LOREN G. LADD, OF PAWTUCKET, RHODE ISLAND, ASSIGNORS TO SMITH, GRANT & CO., OF SAME PLACE.

HOISTING-BUCKET.

SPECIFICATION forming part of Letters Patent No. 290,649, dated December 18, 1883.

Application filed September 20, 1883. (No model.)

To all whom it may concern:

Be it known that we, GEORGE E. NEWELL and LOREN G. LADD, of Pawtucket, in the county of Providence and State of Rhode Island, have invented an Improvement in Hoisting-Buckets, of which the following is a specification.

The object of our invention is to provide a powerful self-loading hoisting-bucket for unloading coal from the holds of vessels; and it consists in the improved construction of the several parts, whereby the bucket is adapted for raising upward through the hatch of a vessel without liability of catching.

Figure 1 is a perspective view of our improved self-loading bucket. Figs. 2, 3, 4, 5, and 6 are detail views illustrating the parts.

In the accompanying drawings, A A' are the two jaws of the bucket, which are pivoted to each other by means of a bar, B, the opposite ends of which enter the pivot-holes made in the pivot-pieces C C', placed at each end of the bucket.

Upon the bar B, between the pivot-pieces C C', is placed the hollow drum D, in the middle of which is secured the sheave E. The rods F F' F' are pivoted at the corners of the bucket by means of the pivot-pins a, and the rods F F', as they rise from the corners of the bucket, converge toward a point over the center of the bucket where the opposite ends of the rods are likewise pivoted by means of a bolt, G, which extends through the eyes b, made at or near the ends of the rods. The rods F' are extended for a short distance beyond the pivot-eye b, thus forming the opposite arms d d', each provided with a perforation, c, adapted to receive an arbor, m, upon which, between the arms d d', is placed the loose friction-sheave H.

Between the upper ends of the rods F F', upon the pivot-bolt G, is placed the flat link e, to which is secured the chain I.

To the periphery of the sheave E are attached the U-formed guides f, adapted to guide the hoisting-chain J upon the periphery of the sheave, the chain J being attached to the sheave by means of the staple or eye g.

At the opposite ends of the pivot-bolt G are secured the flat links h h', from which depend the chains K K', adapted to wind upon the

drum D at opposite sides of the sheave E, as shown in Fig. 1, and the chains K K' are secured to the drum D by means of the eyes i i'. The rods F F', by converging to a point above the center of the bucket, serve to guide the corners of the bucket clear of the sides of the hatch; and in order to prevent the corners of the bucket from cutting into the wood-work, we provide the rods F F' with a bend, j, near their lower ends, as shown in Figs. 1 and 2, thus preventing all possibility of the corners catching at the hatch in rising from the hold of the vessel; and in order to likewise prevent the pivot-joint of the bucket-jaws from catching at the hatch, we either extend one of the pivot-pieces, C, to form an inwardly-directed protecting-bar, L, or attach a separate bar, L, to the opposite ends of the bucket for this purpose, and by means of the oblique inwardly-directed bars extending from the pivot-joints toward a point above the middle of the bucket, and beyond the plane of the rods F F', the pivot-joint will be prevented from catching at the hatch in the upward passage of the loaded bucket from the hold.

Whenever the chain I is firmly held and the chain J slackened, the jaws of the bucket will be thrown open, and by hoisting on the chain J the resulting rotation of the sheave E and drum D will cause a powerful closing of the jaws of the bucket upon the loose coal in the hold by the winding of the chains K K' upon the drum, and the bucket may then be hoisted through the hatch by the simultaneous movement of the chains I and J, as usual in operating such buckets.

We claim as our invention—

1. In a hoisting-bucket, the combination of a hoisting-chain connected to the four corners of the bucket by means of upwardly-converging pivoted rods, and a hoisting-chain operating by means of the sheave and drum, and drum-chains to open and close the bucket, with the opposite inwardly-projecting guide-bars adapted to prevent the pivot-joint of the bucket from catching under the sides of the hatch, substantially as described.

2. In a hoisting-bucket, the combination of the pivoted bucket-jaws with the upwardly-converging rods pivoted within the boundary-line of the corners of the bucket, and pro-

vided with an outward bend at near the pivot-joint, whereby the corners of the bucket are prevented from catching at the hatch upon the ascending movement of the bucket, substantially as described.

3. In a hoisting-bucket, the combination of the pivoted bucket-jaws A A', inwardly-projecting guide-bars L L, pivot-bar B, drum D, sheave E, converging pivoted rods F F' F' F',

the rods F' F' being provided with the arms 10 and 11, the sheave E being pivoted on the bar d d', friction-sheave H, and chains I, J, K, and K', all arranged and operating substantially as described.

GEO. E. NEWELL.
LOREN G. LADD.
